UNITED STATES PATENT OFFICE.

JOHN J. FLANIGAN, OF CHICAGO, ILLINOIS, ASSIGNOR TO DUPLICATOR MANUFACTURING COMPANY, OF CHICAGO, ILLINOIS, A CORPORATION OF WEST VIRGINIA.

MULTIPLE-COPYING MACHINE.

1,272,788.

Specification of Letters Patent. Patented July 16, 1918.

Application filed April 17, 1918. Serial No. 229,009.

To all whom it may concern:

Be it known that I, JOHN J. FLANIGAN, a citizen of the United States, residing at Chicago, in the county of Cook and State of Illinois, have invented certain new and useful Improvements in Multiple-Copying Machines, of which the following is a specification.

This invention relates to multiple copying machines of the general type shown in Letters Patent heretofore granted to me 1,118,119, dated Nov. 24, 1914 and 1,141,702, dated June 1, 1915.

Machines of this type employ a flat horizontal printing bed supported on the machine frame, a platen frame or carriage carrying paper gripping and platen rollers adapted to travel lengthwise over the printing bed, a guide rod mounted on one side of 10 and parallel with the machine frame, and a hinge extension of one end of the platen frame that slidably and rotatably engages said guide rod so as to maintain the platen frame or carriage always in correct relation 20 to the printing bed.

Heretofore the hinge extension of the platen frame has been made integral or rigid with the latter, and this has necessitated the provision of means for effecting vertical adjustments of the ends of the guide rod in order to insure a perfect engagement of the platen roller with the master sheet or copy sheet on the bed during the printing operation, since obviously if the guide rod is even 30 slightly out of perfect parallelism with the printing surface, the platen roll would be slightly tilted endwise and would not engage the full width of the printing bed with uniform pressure.

The purpose or object of my present improvement is to provide a construction which shall insure a more perfect and uniform rolling engagement of platen roller with the surface of the printing bed than has heretofore been possible to attain in machines such as those disclosed in my former patents above identified. Another object is to provide a construction which shall dispense with the necessity of providing adjustments for 40 the guide rod of the platen frame.

With these objects in view, my present invention consists, generally stated, in providing a hinge extension of the platen frame to engage the guide rod as heretofore, which 55 hinge extension, instead of being rigid with

the platen frame, is loosely articulated thereto in such a manner as to afford to the platen frame a limited degree of automatic adjustment to the surface of the printing bed independently of the hinge extension. The manner in which, and the means by which, this improvement is effected are illustrated, in one practical embodiment of the invention in the accompanying drawing, in which—

Figure 1 is a top plan view of the forward end portion of a multiple copying machine having my present improvement applied thereto. Fig. 2 is a vertical section as seen on the line 2—2 of Fig. 1. Figs. 3 and 4 are fragmentary views similar to Fig. 2, but 60 illustrating slightly raised and lowered positions of the platen frame relatively to its hinge extension as compared with Fig. 2; and

Fig. 5 is a sectional detail on the line 5—5 of Fig. 2.

Referring to the drawing, 10 designates as an entirety the machine frame which supports the bed 10' carrying the usual gelatin duplicating band or apron 11, on which in 80 the use of the machine, master sheets and copy sheets such as indicated at 12 are rolled out by an impression device consisting of a platen frame or carriage 13 carrying suitable paper gripping and platen rollers, a detailed 85 description of which will be found in the specifications of my former patents above identified.

14 designates the guide rod for the platen frame which is rigidly mounted at its ends 90 in suitable brackets 15 secured to one side wall of the machine frame; this rod lying substantially parallel with the upper surface of the printing bed. 16 designates a tubular member or sleeve that has both a 95 sliding and relative turning engagement with the guide rod 14, and constitutes a hinge-like extension of one end of the platen frame 13. Instead of making this hinge extension rigid with the platen frame, as heretofore, I connect the two by a loose joint that allows a limited relative vertical movement between them. To this end one end member 13' of the platen frame has formed 100 on its outer face hinge lugs 17, and the member 16 is likewise provided with laterally extending hinge lugs 18 lying along side of the hinge lugs 17. Through the mating hinge lugs 17 and 18 are passed pivot pins or pintles 19; and it will be observed, by ref- 105

erence to Figs. 2, 3 and 4, that the hinge lugs 18 are formed with substantially flat forward surfaces 18' that are slightly separated from the outer face of the frame member 13' that carries the hinge lugs 17. The result of this construction is that the platen frame can have a limited up and down movement relatively to its hinge extension 16 on the pintles 19 as pivots during the 10 traveling movements of the platen frame over the printing bed. Consequently, if the surface of the printing bed is not at all points exactly parallel to the guide rod 15, this is automatically compensated for by 15 the loose joint between the platen frame and its hinge extension which allows the platen frame to accurately follow and uniformly engage the printing bed independently of the hinge extension 16, while being guided 20 and otherwise controlled by the latter. It will be evident that this construction does away with the necessity of vertical adjusting means for the ends of the guide rod 14, and, further that it automatically takes care 25 of and compensates for any slight variation from a perfectly flat form of printing bed.

The herein described improvement also prevents imperfect operation from other causes and conditions which arise in the 30 practical operation of machines of this type, such as an increase in the diameter of the platen roller from accumulations of dirt, and variations in the thickness of the gelatin copying band or apron resulting from 35 absorption of moisture.

It is believed that the nature, purpose and advantages of this invention will be readily understood by those skilled in the art from the foregoing description taken in connection 40 with the accompanying drawing. Manifestly, the results and advantages of the invention are not dependent upon the

precise details of the embodiment thereof herein shown and described, and hence I reserve such variations and modifications as 45 fall within the spirit and purview of the appended claims.

I claim:

1. In a multiple-copying machine of the character described, the combination with a 50 frame carrying a printing-bed, and a guide-rod extending lengthwise of said frame and bed, of a platen frame movable over said bed, and a hinge extension of said platen frame slidably engaging said rod, said extension being pivotally jointed to said platen frame.

2. In a multiple copying machine of the character described, the combination with a 55 frame carrying a printing-bed, and a guide-rod extending lengthwise of said frame and bed, of a platen frame movable over said bed, and a hinge extension of said platen frame engaging said rod with capacity for both sliding and turning movements thereon, said extension being loosely articulated to said platen frame to permit a limited vertical play of the latter relatively to the horizontal plane of said guide-rod.

3. In a multiple copying machine of the 70 character described, the combination with a frame carrying a printing-bed, and a guide-rod rigidly supported on and extending lengthwise of one side of said frame, of a 75 platen frame movable over said bed, and a hinge extension of said platen frame engaging said rod with capacity for both sliding and turning movements thereon, said platen frame and hinge extension having pivotally jointed parts respectively provided with 80 slightly separated opposed faces permitting a limited relative angular movement of said platen frame and hinge extension.

JOHN J. FLANIGAN
